A. FRITZ.

DEVICE FOR AUTOMATICALLY STOPPING TRAINS.
APPLICATION FILED NOV. 23, 1920.

1,383,198.

Patented June 28, 1921.

Inventor:

Olaf Frits.

UNITED STATES PATENT OFFICE.

ADOLF FRITZ, OF MAGDEBURG, GERMANY.

DEVICE FOR AUTOMATICALLY STOPPING TRAINS.

1,383,198.

Specification of Letters Patent. Patented June 28, 1921.

Application filed November 23, 1920. Serial No. 426,083.

To all whom it may concern:

Be it known that I, ADOLF FRITZ, a citizen of the German Republic, residing at Magdeburg, Germany, have invented certain 5 new and useful Improvements in Devices for Automatically Stopping Trains, of which the following is a specification.

This invention relates to a device for automatically stopping a train when running 10 past the signals. Devices having the same purpose have been severally proposed but hitherto it was not possible to use them in actual railroad working. This drawback is partly caused by the fact that such known 15 devices were too complicated and expensive and partly because they were not safe in working. It is the object of the present invention to construct a device of the kind referred to which is as simple as possible 20 and of greatest working safety.

In the accompanying drawing by way of example a modification of the invention is represented; it shows—

Figure 1 a side view and

25 Fig. 2 a front view of a device constructed according to the invention.

The device which is connected to the signal and which operates the mechanism on the locomotive, consists essentially of an inclined plane or plate one end of which may be raised by means of a cam or eccentric 2. The locomotive is furnished with a roller 3 so arranged that when the locomotive passes said inclined plate the roller runs on said 30 plate. The eccentric 2, the shaft 4 and the beveled wheels 5 are so connected with the signal 6 that when the signal moves to the position indicating danger, the eccentric 2 raises the plate 1 and when the locomotive 35 passes the place where the plate 1 is provided, the roller 3 is raised thereby. This

raises the lever 7 and the latter a rod 8 as indicated by the arrow A. Thereby a connecting link 9 is displaced on the pin 10 to the right while a connecting rod 11 is raised 45 and displaced to the left, and the lever 12 is turned to the right and displaces the arm 13 which turns the regulating handle 14 to the right till the steam is cut off. The arm 13 has a slot 15 by which the handle 14 is 50 moved so that the manual operation of this handle is not hindered by the arm 13. The latter is furnished with a lever 16 which operates the brake-valve 17 so that the air brake of the train comes into play and stops 55 the train. By means of the combination of rods 18 the operating lever of a steam whistle 19 may be connected with the arm 13. The roller 3 after having passed the oblique plate 1 may either return to its initial position or it may be held in its working position by means of a pawl (not shown) till the engineer brings it again into its initial 60 position.

What I claim as my invention is:

In a device for automatically stopping a train when running past a signal, an upright rod (8) carried by the locomotive, an arm (11) connected to said rod, a lever (12) influenced by said arm, a slotted bar (13) 70 connected to said lever, said slotted arm simultaneously engaging the lever (14) for turning off the steam and also a lever (16) operating the brake-valve (17) for admitting air to the brakes, substantially as set 75 forth.

In testimony whereof I have affixed my signature in presence of two witnesses.

ADOLF FRITZ.

Witnesses:

ADOLF STEIER,
GUSTAV MEIER.
